UNITED STATES PATENT OFFICE.

HUBERT G. HUSTED, OF OBERLIN, OHIO.

DESIGN FOR A RECEPTACLE FOR COMMUNION-CUPS.

SPECIFICATION forming part of Design No. 27,454, dated August 3, 1897.

Application filed June 30, 1897. Serial No. 643,037. Term of patent 7 years.

To all whom it may concern:

Be it known that I, HUBERT G. HUSTED, a citizen of the United States, and a resident of Oberlin, county of Lorain, State of Ohio, 5 have invented certain new and useful Improvements in Designs for Receptacles for Individual Cups for Communion-Service, of which I hereby declare the following to be a full, clear, and exact description, such as will 10 enable others skilled in the art to which it appertains to make and use the same, the following being a specification, reference being had to the accompanying drawings.

Figure 1 is a top view of a receptacle for individual cups for communion-service, showing my design. Fig. 2 is an edge view thereof.

As shown in the drawings, the leading or

material feature of my design is an elongated rectangular block A, the extremities of which are cut away on the front side by ogee curves 20 B. Circular openings C are pierced through the top and nearly through the block.

Any ornamentation upon the surface may be added, if desired, without affecting the invention.

Having described my invention, what I claim as new, and desire to secure by Letters Patent, is—

The design for a receptacle as herein shown and described.

HUBERT G. HUSTED.
